COLLAPSIBLE FLORAL RACK

Charles O. Gipson, Elwood, Ind., assignor to Heinz
Manufacturing Company, Inc., Elwood, Ind., a
corporation of Indiana

Application September 25, 1946, Serial No. 699,230

2 Claims. (Cl. 248—27.8)

1

The present invention relates to a floral rack of the type which is adapted to be opened to an extended position and which may be collapsed to provide a relatively compact structure facilitating storage and transportation of the rack. The invention more specifically pertains to such a collapsible rack provided with a plurality of hinged prongs which are automatically moved to closed or neutral positions upon folding of the rack.

One of the objects of the present invention is to provide a floral rack embodying a "lazy tongs" mechanism wherein the slide members of the mechanism engage the forward faces or edges of the prongs and swing all of the prongs to the closed position during collapsing movement of the rack.

A further object of the invention resides in providing a groove in the front face of each bar of the rack extending longitudinally thereof, including prongs hinged to the bars within the grooves wherein a portion of the slide members of the "lazy tongs" assembly overlies the grooves and automatically swings the prongs into the closed position upon collapsing movement of the rack.

A more specific object of the invention pertains to a floral rack embodying a "lazy tongs" mechanism for facilitating the extension and folding of the rack with the members thereof so dimensioned and so pivoted that the sliding elements of the "lazy tongs" assembly will engage the prongs and move them to a closed position upon collapsing movement of the rack.

Other objects and features of the invention will be more apparent as the present disclosure proceeds and upon consideration of the accompanying drawings and the following detailed description wherein an embodiment of the invention is disclosed.

In the drawings:

Fig. 1 is a perspective view of a portion of a collapsible floral rack embodying the invention.

Fig. 2 is a side elevational view of a portion of one of the rack bars showing a prong hingedly mounted thereon.

Fig. 3 is a front elevational view of the bar shown in Fig. 2.

Fig. 4 is a longitudinal sectional view of one of the bars.

Fig. 5 is a sectional view of a detail taken on the line 5—5 of Fig. 4.

The invention is directed to a rack which may be erected somewhat like an easel and which may be opened or extended so as to provide a rack structure of a considerable facial area. The

2

rack embodies a so-called "lazy tongs" construction, permitting the opening thereof to an extended position for use and which may be collapsed so that the bars thereof may lie closely adjacent each other, and provide a compact assembly for convenience in storage and transportation. A characteristic feature of the invention pertains to the swinging of the prongs carried by the bars of the rack to a closed or a neutral position upon folding of a rack structure.

A rack exhibiting the invention is shown in the drawings and includes a plurality of bars 10 which are arranged in a substantially parallel relationship. Any number of bars 10 may be employed in the rack in accordance with the desired dimensions of the device and the selected spacing of the bars in the extended or open position of the rack. The rack structure is primarily designed for supporting a plurality of floral pieces on the forward face thereof, and the bars 10 are accordingly supported in the more or less vertical position, somewhat like an easel. The harness or the swingable straps or arms of the "lazy tongs" mechanism in the embodiment illustrated in the drawing are arranged over the forward face of a rack but may, without altering the characteristic features of the invention, be positioned at the back of the bars 10. The "lazy tongs" mechanism includes a plurality of straps 11 and 12 which are pivoted at their lower ends to the bars 10. The straps 11 are connected by rivets or the like to the bars 10 and the lower ends of some of these pivot pins or rivets 14 also pivotally secure the adjacent ends of the straps 12 to the bars 10. The lower ends of the straps 11 and 12 are accordingly attached to the bars 10 and are therefore fixedly secured to these bars but are free to swing about the pivots 14, thereby permitting an extension of the rack to a position as shown in Fig. 1.

The upper ends of the straps 11 and 12 are free to move longitudinally of the rack structure, and it is for this purpose that the upper ends of these members are pivotally attached to slide members 16. These slide members 16 may be of any suitable shape or type, and in the embodiment illustrated in the drawings, comprise sleeves which embrace the bars 10 in such a manner as to permit free sliding movement of each sleeve on the associated bar. The upper ends of the straps 11 and 12 are hinged to the slide members by means of pivot pins or rivets such as shown at 17 in the drawings. The slide members 16 may be formed of metal, and one characteristic feature of the invention pertains to the fact that

each slide member overlies the forward face 20 of the associated bar 10, and the purpose thereof will be more clearly understood as the present disclosure proceeds.

A further feature of the invention pertains to the mounting of the prongs which are shown at 21 in the drawings. The prongs 21 are pivotally attached to the bars 10 in any suitable manner such as by means of rivets 22 which extend transversely through the bars 10. The prongs 21 are freely rotatable about the pivots or rivets 22 and therefore swing to outward positions by action of gravity when the rack bars 10 are in a substantially vertical position. The prongs are prevented from swinging outwardly from the face 20 of the bars 10 by more than a ninety degree movement so that the prongs will be maintained in position to support various articles thereon such as floral pieces or the like. It is for this purpose that the inner ends of the prongs 29 are angular shaped as shown at 29 in Fig. 4. The angular ends 29 engage the bar 10 and arrest further outward swinging of the prongs.

A characteristic feature of the invention pertains to the position of the prongs 21 with reference to the pivots 14 and the length of the straps 11 and 12 so that a slide member 16 moving lengthwise of the associated bars 10 will engage the forward edge 24 of the prong 21 and thereby swing the prong about the pivot 22 into closed position. In Fig. 4 the straps 11 and 12 are shown in the position these members assume upon collapse of the rack with the bars 10 lying adjacent each other, and it will be noted that the portion of the slide member 16 which overlies the forward face of the bar 10 engages the forward edge 24 of the prong 21 during the sliding movement thereof so as to swing the prong 21 to the closed or neutral position.

In the embodiment illustrated in the drawings, the pivot pins or rivets 22 need not be provided with flat ends flush with the lateral faces of the bars 10, since each slide member 16 is provided with a lip 26 which extends upwardly beyond the top end of the sleeve and thereby does not engage nor overlie the ends of the rivets 22 as shown in Fig. 4. The lips 26, however, are of sufficient length so as to engage the forward edges of the prongs 21 and swing the prongs to a closed position and maintain these prongs in the closed position while the rack is collapsed.

In the embodiment illustrated in the drawings, each bar 10 is provided with a groove 28 in the forward face thereof which extends lengthwise of the bar. The bars 10 are then substantially U-shaped in cross section as shown in Fig. 5. In this embodiment the prongs 21 are mounted within the groove 28 so that the pivot pin 22 extends through the legs of the U-shaped channel bars. The end of each prong 21 adjacent the pivot pin 22 is angularly shaped and this angular end engages the bottom of the groove 28 to limit the outward swinging of the prong to a position substantially as shown in Fig. 2. When the prong is automatically pivoted to the closed position as shown in Fig. 4, the prongs will lie within the grooves 28 and in the completely neutral positions of the prongs, the forward edges 24 are substantially flush with the forward face 20 of the bars 10.

The easel structure for maintaining the rack in an erected position includes a plurality of bars 31 which are hinged to some of the bars 10 by means of brackets shown at 32 in the drawings. The bars 31 may be maintained in an

easel-like supporting position by means of arms 34 which are hinged at 41 to the bars 10 and pivotally connected to slide members 36 which may be moved lengthwise on the bars 31. The 5 easel assembly also includes "lazy-tong" straps 38 and 39 which permit the easel structure to be extended and collapsed along with the rack proper.

When it is desired to erect the rack for supporting articles to be displayed on the forward face thereof, the bars 10 are moved from each other into the open position somewhat as illustrated in Fig. 1. The bars 10 in moving away from each other are maintained in substantially 15 parallel relationship by reason of the "lazy-tong" straps 11 and 12 and the slide members 16 move downwardly on the bars 10 and accordingly retreat from the prongs 21. Thus when the bars 10 are erected in a substantially vertical position, the prong 21 swings outwardly to the position illustrated in Fig. 2 where the angularly shaped ends 29 engage the bottoms of the grooves 28 and arrest further swinging movement of the prongs to thus maintain them in article-supporting positions.

The bars 10 are maintained in the substantially vertical position by swinging the easel bars 31 outwardly to the positions shown in Fig. 1 and the arms 34 are moved downwardly about the pivots 41 so as to maintain the easel in a position to support the rack. During the extension of the rack or during the movement of the bars 10 from each other, the "lazy-tong" straps 38 and 39 of the easel assembly permit the bars 31 to move 30 away from each other and accordingly permit the easel to assume an extended position. The floral pieces or other articles to be supported on the face of the rack may then be supported on the prongs 21 and it will be noted that the straps 11 and 12 are positioned under the prongs 21 in such a manner as to prevent the floral pieces or the like from swinging backwardly to the spaces intermediate the bars 10.

Thereafter, when it is desired to collapse the 45 rack into a compact assembly, the bars 10 may be moved toward each other and slide members 16 accordingly move longitudinally of the bars 10. The slide members 16 and that portion thereof over the forward face of the bars 10 engage the 50 forward edges 24 of the prongs and swing the prongs about the pivots 22, whereby the forward edges lie along the face of the bars 10. In the embodiment illustrated in the drawings, the lip portions 26 of the slide members 16 engage the 55 forward edges of the prongs and swing these prongs 21 into the grooves 28. The easel assembly may be folded against the rear face of the rack proper prior to the collapsing operation thereof or after the rack has been collapsed. During 60 the collapsing movement of the rack proper, the easel bars 31 likewise are moved to positions adjacent each other, and maintained in parallel relationship by reason of the "lazy-tong" straps 38 and 39.

65 It will be noted that the prongs of the present rack structure move freely to the extended or article-supporting position by the action of gravity, and these prongs are pivotally moved to inoperative position upon closure of the rack so that the prongs are moved to the neutral positions regardless of the position of the rack during the collapsing movement. Likewise, the prongs 21 are maintained in the neutral positions regardless of the position of the rack after it 70 has been collapsed.

While the invention has been described with reference to the specific structural details, it will be understood that various changes may be made in the device, such as the shape of the prongs and the number of bars, and in the organization of the "lazy-tong" mechanism. Such modifications may be made without departing from the spirit and scope of the invention which is characterized by a slide member of a "lazy tongs" mechanism engaging a prong and moving it to the closed position during the collapsing movement of the rack structure.

I claim:

1. In a collapsible floral rack, a plurality of substantially parallel bars, a prong hinged to each bar and adapted to lie flush with the forward face of said bar and to swing outwardly to an article-supporting position when the rack is erected for use, a sleeve surrounding and slidable on each bar and overlying the forward face of said bar, crossed straps constituting "lazy tongs" attached at one end to said bars to pivot about fixed points thereon, pivots connecting the other ends of the straps to said sleeves, and the length of said straps and the position of said hinged prongs being such that when the bars are moved towards each other the sleeves engage the forward edge of said prongs and swing the same to a position along said bars.

2. In a collapsible floral rack, a plurality of substantially parallel bars, each of said bars having a longitudinal groove in the forward face thereof, a prong hinged to each bar and adapted to lie within the groove thereof and to swing outwardly to an article-supporting position when the rack is erected for use, a sleeve slidable on each bar, a lip carried by each sleeve and overlying said groove, crossed straps constituting "lazy tongs" attached at one end to said bars to pivot about fixed points thereon, pivots connecting the other ends of the straps to said sleeve, and the length of said straps and the position of said hinged prongs being such that when the bars are moved towards each other said lips engage said prongs and swing the same into said grooves.

CHARLES O. GIPSON.
